COAL-CUTTER CHAIN

Stephen Shepherd-Smith, Beaconsfield, England,
assignor to Austin Hoy & Company Limited,
Aylesbury, England, a British company

Application July 14, 1947, Serial No. 760,760
In Great Britain November 6, 1941

Section 1, Public Law 690, August 8, 1946
Patent expires November 6, 1961

5 Claims. (Cl. 262—33)

1

This invention comprises improvements in or relating to tool-carrying chains for coal-cutters and like apparatus, the chain being of the usual edge-cutting type—that is to say the chain is made of links hinged to run in a groove round the edge of a flat jib and carries tools, usually termed picks, which when the chain is in place on the jib will be more or less symmetrically disposed about the central plane of the jib and will project away from the edge of the jib so that in use they cut a flat groove into which, as it is cut, the jib can be entered. It is an object of the invention to provide a pick-carrying chain of which the parts are simple, and in which provision is made for carrying picks at a number of different angles and for overcoming the effects of wear so that the chain has a long life.

In such coal-cutter chains it is usual to provide pick boxes, which may be forged from steel but are sometimes steel castings, or are built up by welding, and which are furnished with holders for picks, the holders in successive pick boxes being set at different angles so that the picks each cut in a line which differs from the line of the pick in front of it in the chain and thereby a groove can be cut in the coal, or the floor beneath the coal, which is wider than the jib on which the chain runs. Similar apparatus is employed for the cutting of other minerals as well as coal.

The term "coal cutter chain" as used herein is intended to include such chains when used for cutting other minerals as well as coal.

As the chains run they wear against the jib and eventually become too much worn away for further use. The present invention contemplates the manufacture of a reversible chain, which, when worn away by use can be reversed to bring fresh wearing parts into engagement with the jib and so have a fresh lease of life.

The present invention provides a coal cutter chain wherein each of the chain links has an apertured projection at one end and a fork at the other, the fork being constituted by side plate portions which are separated from one another throughout the depth of the link as far as their junction with the projection and being adapted to support between them a separate tool-carrying boss, and wherein tool-carrying bosses are welded to the side plate portions on a number of the links of the chain.

2

Preferably the tool-carrying bosses are of circular shape where they rest upon the side-plate portions of the links so that they bed down the side-plate portions and also can be fitted in a number of different angular positions. While it has previously been proposed to weld on tool-carrying bosses having semi-circular under portions to links in tool-carrying chains, there is an advantage in the combination of such tool-carrying bosses with the separated side-plate portions according to the present invention because as the lower parts of the bosses fit down well between the side-plate portions they are supported effectively by widely separated lines of welding on the two side-plate portions and the picks are brought down closer to the line of welding.

While each link may consist of one piece comprising the apertured projection and the separated or forked side portions, preferably according to the present invention each link of the chain consists of two similar forgings, one comprising one side-plate portion of the link and the other comprising the other side-plate portion, and each of which comprises part of the apertured projection end of the link, these side members being assembled side by side in the chain and (in those links which carry tools) united by welding along one edge to the tool-boss.

The preferred construction according to the present invention also provides means for lateral adjustment of the width of the chain to take up wear. These and other features of the invention will be more clearly understood from the following description which is given by way of example of specific forms of chain in accordance with the invention.

According to a further feature of the invention a pick-carrying chain of the edge-cutting type above referred to is characterised by the fact that the links, including the side plates thereof but excluding the pick-holding bosses, are substantially symmetrical about a plane containing the axes of the hinge-pins so that on detachment of the bosses the links can be reversed and pick-holding bosses can be welded on to the opposite edges of the side plates from those to which they were welded previously.

As a result, according to the present invention, each link of the chain may consist of two

similar forgings, steel-castings or welded elements, one for one side of the link and the other for the other side of the link, which can be put together in the chain side by side and each of which (in those links which carry picks) is united in the finished chain by welding along one edge to the pick-boss. The invention comprises the side members per se as well as the complete chain.

Referring now to the accompanying drawings:

Figure 1 shows a side elevation of part of a coal-cutter chain constructed according to the invention.

Figure 2 is a plan of the chain illustrated in Figure 1, with the tool-bosses removed, and their position indicated only in chain-line.

Figure 3 is a cross-section through the line 3—3 in Figure 1.

Figure 4 is a perspective view of one side member of a link as used in the construction of chain shown in Figure 1.

Figure 5 shows a modification wherein alternate links only of the coal-cutting chain are tool-carrying links.

In carrying the invention into effect, according to one form and as applied by way of example to a pick-carrying chain for a coal-cutter, the chain consists of a series of links 11, Figures 1 to 3, jointed together by riveted hinge pins 12. Each of the links 11 comprises two side members 13, which may be formed either as forgings or castings, and arranged side by side, one of these side members being shown in Figure 4. Each side member 13 consists of a flat platelike body portion 14 which has an eye 15 at one end to receive a rivet 12 which constitutes a hinge pin. At the other end the body portion 14 is recessed at 16 to accommodate the convex end portion of the eye 15 of the next link. The body portion 14 is integral with a boss 17 which projects inwards from one side of the body portion. The boss 17 is pierced with a hole 18 and constitutes part of the apertured portion hereinbefore referred to, the aperture 18 serving to receive a liner 19. Within the liner is a bushing 39.

On the outside face of each side member 13 there are two flanges 20 and 21 one extending along the upper edge and the other along the lower edge of the side member between the hinge pins constituted by the rivets 12. The flanges 20 and 21 are formed of such dimensions that they can run in one side of the usual T-slotted jib which is provided on a coal cutter. The middle of the flat body portion 14 between the flanges 20 and 12 is pierced so as to provide a dirt-extrusion aperture 22 hereinafter more fully referred to. The inner face of the body portion 14 in the vicinity of the eye 15 is machined to provide a shallow slot 23 which extends longitudinally on each side member 13, this slot cutting across the eye diametrically as shown in Figure 4. The purpose of the slot 23 is to receive two corresponding projections 24 which project from one end (or if desired from both ends) of the bushing 39 and prevent rotation of the bushing as hereinafter described. The slots 23 might be disposed crosswise instead of longitudinally if desired.

Two side members 13 as just described are assembled together to form one complete link 11. They are assembled so that the two bosses or projections 17 embrace a single liner 19. There is then inserted a bushing 39 having one or more keys or projections 24, as already described, which projections are able to enter one or both

of the slots 23 milled across the eyes 15 of the adjacent side members of the next link of the chain and by such engagement prevent rotation of the bushing 39 relatively to said next link.

5 The two side members 13 of each link 11 thus assembled together and containing a liner 19 and bushing 39 are caused to enter between the eyes 15 of the side members 13 of the next link of the chain and the rivet 12 is inserted through the bushing and eyes and riveted over. Thus the chain is built up link by link. The rivets may be made, as shown in Figure 3, shouldered at one end to accommodate a conical washer, thus simplifying the riveting-up process.

15 It will be observed that the side members 13 of each link are spaced apart from each other by a distance equal to the depth of the two bosses 17. To the edges 26 of the links 11 there is welded a tool-boss 27, Figures 1 and 3. The 20 tool-boss 27 may be either forged or cut from a bar of suitable section or may be cast and in section may be either circular or egg-shaped. The rounded bottom portion of each tool-boss 27 rests upon the edges 26 of the side members 25 13 of the link to which it is attached and owing to the rounded shape the boss can be tilted over to any desired angle before welding and will fit equally well in any position. Each of the tool-bosses 27 is machined or drifted through 30 with a rectangular pick-carrying aperture 28 which usually extends in a plane at right-angles to the plane in which the rivets 12 of the chain lie.

One or both of the end faces of each tool-boss 27 is drilled and tapped to receive a pick-securing set screw 29. After welding the tool-bosses 27 to the edges 26 of the side members 13 of the links 11 the chain is complete.

Conveniently each tool-boss 27 will be welded 40 securely to one of the side-members 13 of its link and merely tacked to the other as this facilitates subsequent removal of the tool-boss for overhaul purposes.

By the employment of a tool-boss of which 45 the bottom is of semi-circular or approximately semi-circular shape the tool-bosses may be readily welded in various positions with respect to one another in order to obtain any desired pick-angles. In addition, the particular shape 50 of the bottom of the tool-bosses provides a constant angle for welding between the bosses and the side members of the link.

It is to be noted that the links 11 as above 55 described are symmetrical about the plane which contains the axes of the rivets 12. The flanges 21, Figures 1 and 3, run in the sides of the T-slotted jib of the coal-cutter (which thus constitute guides for the chain). These flanges 21 are liable to wear in the jib on account of 60 the lack of lubrication, the presence of stone dust and so forth. When the flanges 21 have become worn to such an extent as to be unserviceable the chain can be reversed if the pick-bosses 27 are first broken-off along the lines of welding 65 and any additional metal ground flat, thus permitting the unworn flanges 20 to run in the guides of the jib. The pick-bosses 27 are then re-welded to the links 11 along the opposite edges to those of the side members 13 which had been previously running in the jib. In general, when the chain is thus reversed it will be found that the liners 19 and bushings 39 are worn. It will be recollect that the bushings 39 are prevented from rotation by the

engagement of the projections 24 with the slot 23 on the inner faces of each link 11. Each side member 13 has a slot 23 on its inner face and if each bushing is reversed so that it engages the slot on the opposite side member of the link, the unworn portion of the bushing will be in tension and the chain will then be brought back into pitch and gain a further lease of life also in this respect. From this it will be seen that the wear which necessarily takes place at the joints, due to oscillation, is absorbed only by the liner 19 and the bushing 39 and that wear is prevented from taking place between the liner 19 and link member 13. Furthermore the liner 19 can be easily and cheaply replaced by a new one when such wear has taken place.

As only a single liner 19 is used in conjunction with each pair of bosses 17 these liners impart lateral stiffness to the links since the side members 13 of the links in effect are connected together by these liners.

The riveting and breaking of the riveting of rivets 12 is greatly facilitated by the use of shouldered rivets in conjunction with conical washers 25.

The apertures 22 which are cut in the side members 13 of the links 11 and are disposed between the flanges 20 and 21 for the purpose of dirt-extrusion permit the teeth of the sprockets on which the chain runs, which teeth enter the spaces 30 between the links during running, to force any dirt outwardly through these apertures. Dirt tends to enter the spaces 30 while the chain is cutting but as it can be forced out by the sprocket teeth through the openings 22 it does not accumulate or tend to jam against the undersides of the tool-bosses.

It is not essential that a tool-boss 27 should be secured upon every link 11 of the chain and in Figure 5 a chain is shown in which idle links 31 alternate with links 11 carrying tool-bosses 27. The idle links 31 comprise, however, two side members 13 which are similar to those from which the links 11, carrying the tool-bosses 27, are made. Every link therefore of the chain can be forged from a single set of dies and the special intermediate links of the typical present-day chains, which serve only as a connection between successive pick-carrying links, are eliminated.

Furthermore provision is made for lateral adjustment of the width of the chain so that it may be made to fit the sides of the T-slot of the jib even if worn, or to fit any width of slot in jibs already in use. Adjustment to bring about increase in width is effected by inserting a washer 32 of suitable thickness, as shown in Figure 3, between the bosses 17 of each pair of side members 13 and the insertion of such washers can be conveniently effected when the chain is being reversed as above described.

The rivets 12 are conveniently made of large diameter to afford ample strength and are left short at one end as this facilitates both riveting and subsequent removal of the rivets for purposes of overhaul or reversal of the side members. It will be noted that the rivets do not take the wear of the joint.

The chain illustrated in Figure 5 is similar to the foregoing in all respects except that the tool-bosses 27 are mounted on alternate links.

It will be appreciated that every link 11 in the chains above described may act as a driving link whereas in chains of the second type above referred to in which idle links alternate with pick-

boxes, the chain will engage the sprocket teeth in idle links and the sprocket teeth have to be spaced out accordingly. It is therefore possible with a chain according to the invention to space the sprocket teeth to engage every link and thus to double the number of sprocket teeth and reduce their wear, thereby increasing the life of the chain and ensuring smoother running. The chain will, however, run on an ordinary sprocket just as well as existing chains do.

Instead of constructing the links from forgings, the links can, if desired, be fabricated from pieces cut from steel channel section, the flanges of which will constitute the flanges for engaging with the T-slots of the jib, and bosses being placed on the opposite face of the channel to that carrying the flanges and welded or attached in any other convenient manner. The bosses in such a case can be cut from circular, elliptical or other suitable section bar steel. For another construction each link 11 can be formed as one unit either by forging, casting or fabrication.

The bosses 17 on the side members 13 of the links 11 may be of elliptical, semi-elliptical or other suitable rounded form instead of circular as above described, and in fact they are shown slightly elliptical in the drawing to allow room for thicker sprocket teeth.

I claim:

- 30 1. A coal-cutter chain comprising a series of identical links jointed together by hinge-pins wherein each link comprises identical side plates, spaced apart to carry between them welded-on tool-carrying bosses, each of the side plates having short flanges along each edge of sufficient length to guide the link in the jib of the coal-cutter and to afford shelves for the welding but not long enough to overlie the joint at the hinge-pins, the links, apart from the bosses, being substantially symmetrical about a plane containing the axes of the hinge-pins, so that, on detachment of the bosses the links can be inverted and tool-carrying bosses welded on to the opposite edges of 45 the side plates from those to which they were welded previously.
- 25 2. A tool-carrying chain as claimed in claim 1, wherein the side plates of each link are brought together at one end by reason of being joined to 50 an eye which embraces the centre of a hinge-pin and are separated at the other end and comprise eyes also at that end to embrace the outer ends of the hinge-pin of the next link.
- 35 3. A coal-cutter chain according to claim 1, each tool-carrying boss being convex on its underside where it rests upon the side plate portions of the links and of sufficiently small radius to bed down substantially between the side plate portions.
- 40 4. A side-member for a link of a tool-carrying chain according to claim 1, comprising a plate-like member having flanges on two opposite edges and having eyes for hinge-pins immediately disposed between the flanges or guides, the formation of the plate-like member being symmetrical about the plane joining the axes of the hinge-pin eyes so as to permit the links of a chain incorporating these side members to be inverted to prolong the life of the chain.
- 45 5. A side-member for a link for a tool-carrying chain, as claimed in claim 4, wherein the eye at one end of the side-member is inset from the plane of the plate-like side member so that when 55 assembled in the chain it can lie inwardly of the

eye at the adjacent opposite end of the next link
of the chain.
